UNITED STATES PATENT OFFICE.

LESLIE McHARG, OF FREEPORT, NEW YORK.

PIER DOOR.

Application filed August 30, 1921. Serial No. 496,800.

To all whom it may concern:

Be it known that I, LESLIE McHARG, a citizen of the United States of America, residing at Freeport, in the county of Nassau and State of New York, have invented certain new and useful Improvements in Pier Doors, of which the following is a full, clear, and exact description.

In a patent granted to me on February 22, 1921, No. 1,369,425, I have shown and described a pier shed door in which the door is composed of two sections the lower section of which, by suitable means, is raised until it fully overlaps the upper section, whereupon both overlapping sections are simultaneously caused to travel upwardly and outwardly by grooved guides with which they engage into a substantially horizontal position.

In the mechanism shown in the patent for accomplishing this result a counterbalancing weight is used on each side of the door, and two pulleys are employed at opposite ends of a rotary shaft over which chains carrying the weights run, one end of each chain being connected to the bottom of the edge of the lower section and the other to an intermediate part of the edge of the upper section.

It resulted from this arrangement that more space was necessary for the door and its counterbalancing weights than was desirable, and that when the door was fully opened the angle of the chains connected with the middle of the upper section to the normal plane of the pulleys to which said chains led was such that the chain was liable to run out of the pulley groove, or caused undue friction and wear on the pulley. These defects it was my object to avoid in devising and constructing the form of lifting mechanism upon which is based my present application for Letters Patent.

My improvements, in general terms, consist in dispensing with the overhead rotary shaft in the use of a single weight connected to lifting chains running over a special arrangement of pulleys, and in swivelling that pulley at each side of the door over which runs the chain connected with the middle of the upper section of the door, so that when the door is fully opened or substantially so,

the pulley will assume an angle to the vertical which corresponds to and compensates for the angle of the chain.

These improvements are illustrated in the accompanying drawings, in which:

Figure 1 is an edge view in elevation of the improved door.

Fig. 2 is a sectional view of one side of the door on the line 2—2 of Fig. 1.

Fig. 3 is a front elevation of the door.

Fig. 4 is a top plan view of the same.

Fig. 5 is a detailed view of one form of a part of the lifting mechanism; and,

Fig. 6 is an illustrative diagram to illustrate the operation of the door.

The door proper may be composed either of two sections adapted to overlap, or of a single section, since the character of the device as a whole requires but little headroom and is effective for operating either kind or style of door. At each side of the door a channelled or other proper guide 1 is employed, by means of which the door 2, when closed, is held in a vertical position by projections 3 which in practice should be rollers to avoid friction, but when raised, is caused to assume a nearly horizontal position, as shown in dotted lines in Fig. 1.

The theory of the construction and operation of the controlling means is shown in Figs. 4 and 6, to which reference for the moment is made. At each side of the door 2 and above it, two loose pulleys 4, 5, 6, 7 are supported by suitable brackets 8 and on one side of the door a shaft at right angles to the plane of the door is mounted on which are four pulleys 9, 10, 11, 12 as nearly as practicable, in the plane of the others, and a winding pulley or sprocket 13. Of these pulleys 9 and 10 are fixed to the shaft and 11 and 12 are loose. Over pulley 13 passes a hand chain 14, shown in Fig. 3, by means of which the pulleys 9 and 10 are rotated.

Chains or preferably wire ropes 15, 16 and which I shall hereinafter refer to as cords, run over the pulleys in the following manner, the pulleys being shown in the diagram Fig. 6, as of different diameters for sake of illustration. One end of cord 15 is connected to the bottom of the edge of the door and runs up over the pulley 4,

thence over fixed pulley 10, thence over one of two idlers 17 in a bracket from which the weight 18 is suspended, thence over the loose pulley 12, thence over pulley 5, and 5 down to the middle or approximately such point on the same edge of the door.

In like manner the cord 16 passes over pulleys 6, 7, 9, 11 and the other idler 17, so that when the pulleys 9 and 10 are rotated by the hand chain 14, the door is 10 drawn up by the combined action of the weight 18 and the force applied to the fixed pulleys.

As the door rises its upper edge follows 15 the guides 1 and the door ultimately lies out in the substantially horizontal position shown in Fig. 1, but in this position it will be seen that the portions of the suspending cords connected with the middle of the door 20 lie at an angle to the normal plane of the pulleys over which they run. This is shown clearly in Fig. 1. Under such circumstances the cords are liable to pull off from the grooved pulleys, to prevent which 25 the two pulleys 5 and 7 are swivelled, as indicated, so that in swinging they follow the angle of the cords as indicated in dotted lines in Fig. 1.

To permit this movement of the pulleys 30 without interfering with the cords the driving pulleys 9 and 10 must be higher than the loose pulleys over the door corners as indicated in Fig. 6, or the cords must pass substantially through the centers around 35 which the swivelled pulleys turn, as indicated in detail in Fig. 5, where the cord is shown as passing through an opening 19.

This pier door is an improvement on those 40 now in general use in that it economizes space and parts. The power required to open and close the door is uniform in all positions of the door, and the effects of friction are greatly reduced. The means

for controlling the door are very simple and not liable to wear or derangement.

What I claim is:-

1. The combination with a pier shed door of a driving shaft for controlling the same supported at one side of the door, four pulleys on said shaft, two fixed and two loose, 50 two loose pulleys over each upper corner of the door, cords passing over each pair of loose and the pair of fixed pulleys, and a weight carried by the same, the said cords being connected respectively to the bottom 55 and the middle of the edges of the door.

2. The combination with a pier shed door which in opening assumes a horizontal position, of two loose pulleys over each upper corner of the door, weighted cords running over such pulleys and means for operating the same for opening or closing the door, one end of each cord being connected to the bottom and the other end to the middle portion of the edge of the door, and that 60 loose pulley of each pair over which the cord connected to the middle of the door runs being swivelled so as to follow the angle of such cord when the door is brought 65 to a horizontal position.

3. The combination with a pier shed door which in opening shifts from a vertical to a horizontal position, of a pair of loose pulleys over each upper corner of the same, one 70 of each pair being swivelled, two driving and two loose pulleys at one side of the door and weighted cords passing over all of said pulleys and having their ends connected respectively with the bottom and middle points of the edges of the door, the end of the cords connected with the middle running 75 over the swiveled pulleys, for the purpose set forth.

In testimony whereof I hereto affix my signature.

LESLIE McHARG.
